UNITED STATES PATENT OFFICE.

CHARLES E. EGAN, OF CHICAGO, ILLINOIS, ASSIGNOR, BY MESNE ASSIGNMENTS, TO WESTERN TELEPHONE MANUFACTURING COMPANY, OF CHICAGO, ILLINOIS, A CORPORATION OF ILLINOIS.

TELEPHONE-SWITCHBOARD.

SPECIFICATION forming part of Letters Patent No. 732,931, dated July 7, 1903.

Application filed May 1, 1897. Renewed June 5, 1899. Serial No. 719,418. (No model.)

To all whom it may concern:

Be it known that I, CHARLES E. EGAN, a citizen of the United States, residing in Chicago, in the county of Cook and State of Illinois, have invented a new and useful Improvement in Telephone-Switchboards, of which the following is a specification.

This invention is designed to render the switchboard very compact and to furnish an exceedingly practicable construction which shall also tend to lessen the liability to mistakes on the part of the operator.

In the drawings, Figure 1 is a section of the board in connection with a diagram of the circuits. Fig. 2 is an enlarged section, and Fig. 3 is an enlarged front view of one of the jacks and its drop.

In said drawings, A A represent a series of metal sockets or jacks secured in the front A' of the switchboard. They are secured in place by screws A², passing through the front of the board, and each is adapted to receive one of the plugs B, attached to the flexible conductor B' and serving to connect the subscribers in the usual manner. At opposite sides of each jack and in such proximity thereto as to enable the attendant to operate them with the same hand whereby she inserts the plug into the jack are movable arms C and D, preferably of spring metal and both capable of slight movement. All the arms are supported in the rear upright A³. The arms C are moved against the contact-pieces C', which are in circuit with the jacks, and the arms D are normally in contact with contact-pieces D' and are movable away therefrom and into contact with contact-piece D².

The drops E are located at their corresponding jacks, preferably as seen at Figs. 2 and 3. In order to economize the surface room required by this feature of construction, I prefer to cut an opening or slot E' in each drop large enough to enable the drops to set over the jacks. I also prefer to hinge the drops to the board, as shown at E². The magnets E³ for releasing the drops are located in the rear of the front A' and preferably directly back of the respective jacks to which the drops belong. I also prefer to make the cores of the

magnets hollow and to insert therein vulcanized fiber E⁴, which will receive the inner end of the screws A², and thus enable the magnets to be supported by said screws. The same screws also serve as a means of attaching the jacks to the board, the jacks having openings through which the screws may be passed and the heads of the screws being seated against the inner ends of the sockets, as seen at Fig. 2. The catch-levers E⁵, which hold the drops in their normal positions, are secured in the swinging armatures E⁶ of the magnets and project over or through the board-front A', as shown.

The electric circuits may be substantially as indicated at Fig. 1. The primary circuit F includes battery F', transmitter F², and induction-coil F³, secondary circuit G including said induction-coil and receiver G', which is kept at the operator's ear at the central station, as usual. The secondary circuit is connected to each arm C by branch wires G² and also to the common return-wire or to the ground. J is the call-generator circuit, also connected to the return-wire H, and includes the electromagnetic generator J'. It is also connected to each contact-point D² by wires J².

The telephones shown at K K are connected to return-wire H by branch wires H' and to the arms D of their respective jacks by wires K' K'. Each jack is also connected to its corresponding telephone-wire K' by a wire L, leading to the rear end of arm D. The drop-magnets are connected upon one side to the contacts D' by wires E⁷, and upon the other side by branch E⁸ and wire E⁹, connecting with the circuit-wire H. The circuits above set forth, with the single exception of the one operating the drop, are fully described by me in my application filed December 5, 1896, as Serial No. 614,530, as are also the construction of the jack and the movable arms and their mode of operation, and those features form no part of the present invention.

The drop-magnets are each covered with casings of magnetic metal, such as iron or steel, in order to break up the lines of force and prevent induced currents therein. This

magnetic armor may be and preferably is formed by closely coiling wire around the magnet, as shown at M. I find that by the use of this armor upon the drop-magnets 5 much of the cross-talk incident to telephone systems may be prevented.

By my present invention the board operator can have no excuse for not reinstating the drop in its normal position, as she can do this 10 with the same hand with which she manipulates the plug and at the same time.

I claim—

1. The combination with a jack projecting in front of the board of a slotted drop hinged 15 to the board and setting over the jack, substantially as specified.

2. In a telephone-switchboard the combination with a jack projecting in front of the

board, of a drop-magnet located behind the board and directly in line with the jack, said 20 magnet being provided with a vulcanized-fiber core, a drop, and a screw adapted to connect the core to attach the magnet to the board.

3. In combination with the jack projecting 25 in front of the board, a drop-magnet having an insulating-core and located back of the board and directly in line with the jack, a drop, and a single screw acting to secure both the jack and the magnet to the board, substantially as specified.

CHARLES E. EGAN.
